CLOCK

Cecil B. Woofter, Crystal, Minn., assignor of one-half to
Donald E. Harley, St. Paul, Minn.

Application February 23, 1956, Serial No. 40,302

Term of patent 14 years

(Cl. D42—7)

FIG. 1

FIG. 3

FIG. 2

Figure 1 is a front elevational view of a clock showing my new design.

Figure 2 is a top view (partially broken away) of the clock of Figure 1.

Figure 3 is a side view of the clock of Figure 1.

The dominant feature of this invention is shown in unbroken lines in the drawing.

I claim:

The ornamental design for a clock, as shown and described.
